MOTOR DRIVEN ILLUMINATED ENDLESS
BAND SIGN APPARATUS

Isidore Holsman, Chicago, Ill.

Application February 15, 1935, Serial No. 6,666

11 Claims. (Cl. 40—32)

The present invention relates to a motor driven illuminated endless band sign apparatus, and more particularly to a small compact box-like structure in which an endless band, of greater length than the structure, is arranged to be continuously moved along an opening in a side wall of the structure and illuminated by means within the structure for displaying the matter borne by the band as it is moved.

10 The invention further contemplates a case or box so constructed as to be readily portable and adapted to be placed in any convenient position for display or advertising purposes, and in which an endless band of inherently stiff yet resilient material, such as celluloid, is impressed with suitable display matter and continuously moved along an opening in a side wall of the box.

It has heretofore been known that endless band signs have been devised, but in the main, the bands utilized have been constructed of cloth, paper, or the like material which is readily torn, and which becomes snarled in the magazine or storage portion of the apparatus so as to resist movement of the band for advertising purposes. Furthermore, the bands for the most part now in use have the letters thereon formed by punch marks outlining the letters, so that the result is indistinct and the effect produced is dim and far from pleasing or satisfactory. The invention is directed to an endless band type of sign wherein the major portion of the band is folded or grouped in convolutions within a magazine or storage portion of the apparatus so that necessarily the band must be of sufficient self-contained rigidity to fold and unfold without becoming tangled. Furthermore, the structure must be so constructed as to enable ready withdrawal of the band from the storage space or compartment without the band, at any time, becoming wedged against advancement which wedging, of course, would cause breakage of the band rendering the apparatus useless.

The present invention contemplates a machine of the character mentioned, wherein the band is of celluloid or other like material, inherently stiff and yet resilient enough for the purpose intended which band has advertising matter thereon, preferably photographically made. Such a band has been found to very readily fold or form convolutions in the magazine, and to readily unwind or draw out of the magazine as the band is moved by the motor of the apparatus.

It has been found that a band of celluloid of the character generally employed for motion picture films possesses the requisite characteristics

desired and by the use of such a band a long one, sometimes of several hundred feet, may be expeditiously employed in the apparatus of the present invention. Such film lends itself very readily to the formation of convolutions or folds 5 and moves easily through the apparatus so that a motor of small size and power, may be used.

The celluloid band or film, of the present invention, may be so treated as to cause the characters thereon to appear as transparent and 10 with the background opaque, so that the characters stand out pronouncedly and boldly thus requiring a source of illumination which can very readily be arranged within the box or casing of the present invention.

An object of the present invention is to provide 15 a motor driven illuminated endless band sign apparatus which is of readily portable size and shape and consisting of simple devices and parts.

Another object of the present invention is to 20 provide means for readily changing the appearance as to color of the displayed matter on the endless band.

A further object of the present invention is to 25 provide, in an apparatus of the class described, a storage space or magazine for the folded or convoluted portions of the band with bottom and side walls of such material as will not prevent ready movement of the folds or the convolutions of the band into and out of and through the 30 magazine.

A further object of the present invention is to 35 provide an endless band sign of the type described wherein the band utilized possesses sufficient inherent stiffness to stand in edgewise position and also so that it may be readily folded or convoluted without offering undue resistance to advancement into or out of the storage space or magazine.

A still further object of the present invention 40 is to provide a novel driving arrangement for the movement of the band whereby the direction of entry of the band into the storage space or magazine may be varied within certain limits.

The invention has for a further object the 45 provision of means for guiding the top and bottom edges of the portion of the film or band as it is moved along the opening in the side wall of the apparatus so that the film may be prevented from accidental displacement with respect to the light source and thereby assure at all times a clear cut fold and readily observed advertising or display medium.

50 A further object of the present invention is to 55

provide, in an apparatus of the class described, means within the magazine or storage space for preventing the folds or convolutions of the band or film from being vertically displaced one with respect to another and thus preventing coiling or clogging of the folds or convolutions.

The above other and further objects of the present invention will be apparent from the following description, accompanying drawings, and 10 appended claims.

The accompanying drawings illustrate various embodiments of the present invention and the views thereof are as follows:

Figure 1 is a top plan view of one form of the 15 present invention, with the cover and front side wall of the box or case removed, showing one form of the driving means for the band or film and illustrating an elongated single incandescent bulb as the source of illumination for the band 20 as it is moved along the opening in the side wall.

Figure 2 is a longitudinal vertical, fragmental, sectional view taken substantially in the plane indicated by line II—II of Figure 1.

Figure 3 is an isometric view of another form 25 of casing or box of the present invention.

Figure 4 is an enlarged fragmental detail view showing one manner of means for securing a relative angular adjustment as to the driving roll and its idler utilized for moving the band or film 30 through the casing and adjustable to vary the direction of film travel from the driving roller.

Figure 5 is an enlarged transverse vertical sectional view taken substantially in the plane indicated by line V—V of Figure 1.

Figure 6 is a transverse vertical sectional view taken substantially in the plane indicated by line VI—VI of Figure 1.

Figure 7 is a top plan view of another casing or box, constructed in accordance with the principles of the present invention, and showing an inserted plate applicable over the storage compartment or magazine serving as hold-down means for the folded or convoluted portions of the film or band within such space or magazine.

Figure 8 is a transverse vertical sectional view through a casing of the form of Figure 7, showing the top applied to the casing and the relative relation of the hold down plate over the storage space or magazine.

Referring to the figures of the drawings, the casing therein shown comprises a box E having a lid or cover G with which is integrally formed the side wall 54 having an offset portion 55 in it in which is an elongated opening 56. The integral side wall 54 is not hinged to the box E but fits thereon in close engagement. The lower margin of the wall 54 may be provided with an inturned flange 57 for fitting underneath the bottom of the box along the open side which is 60 normally closed by said side wall 54.

For convenience in terminology, the wall 54 will herein be designated as the front wall, although it might be any other wall of the casing as desired.

The cover G is, a short distance inwardly of the front wall 54, provided with an elongated opening 58 for receiving an edge glow plate 59. The ends of the plate are received in channel brackets 60, suitably secured to the top as by 70 screws or bolts 61. Inwardly of the top B, the ends of the plate 59 are carried in stirrups 62 suitably secured to the under side of the top G adjacent the ends of the opening 58. Between the plate 59 and the front wall 54 of the box, the cover is provided with a plurality of vents

or louvres 63 through which heat from within the box may pass to the atmosphere.

Referring to Figure 1 of the drawings, a motor designated generally as H, is suitably supported on a plate 64 which is mounted in spaced relation to the bottom of the box, on feet 65, which may be of resilient material such as rubber or rubber composition or the like. The plate 64 is secured to the bottom of the box by bolts or screws 66 passing through the plate and the several feet 65. The motor H is so mounted on the plate 64 that its shaft 67 projects in a horizontal direction between the plate 64 and the bottom of the box. The shaft is provided with a worm 68 which meshes with a worm wheel 69 secured to an upstanding spindle 70 which is keyed to a driving roller or sprocket 71. The roller or sprocket 71 is preferably cored to receive lubricating material 72 in its interior, which interior is normally closed by a ring 73 surrounding the upper end of the spindle 70 within the interior of the roller. The roller is, on its periphery, provided with a plurality of teeth 74 for meshing with holes 75 formed along the top and bottom margins of the film F.

The film F is preferably made of material which is inherently rigid and stiff and yet pliable, such, for instance, as celluloid or the like. The film is preferably provided with a plurality of marginal folds or perforations 75 for cooperating with the teeth or pins on certain of the rollers. Any suitable wording, display matter or the like may be applied to the film by printing, photographically or otherwise, as most convenient and satisfactory for the purpose intended.

Mounted on top the plate 64 and pivoted to swing about the spindle 70 as a center is an adjusting plate 76 carrying an upstanding spindle 77 on which is rotatably mounted an idler roller 78. This roller is counterbored to receive lubricating packing 79 and its interior is closed by a ring 80 about the spindle 77. The adjusting plate 76 is adapted for limited rotative movement about the spindle 70 as a center by means of a slot 81 in the plate through which passes a screw 82 threaded into the plate 64. By swinging movement of the adjusting plate 76 about its center, the angular relationship of the idler roller 78 with respect to the driving roller 71 may be adjusted to thereby change the direction in which the film F leaves the driving roller and enters the magazine or storage space of the box. Two positions of adjustment are shown in Figure 8 and also two directions of film travel are there illustrated.

The major portion of the interior of the box or casing E constitutes a storage space or magazine K in which folded or convoluted portions of the film F are housed, because of the fact that normally the length of the film F is much greater than the length of the box and excessive length is thus accumulated in folds or convolutions within the magazine K. As a floor for the bottom of the magazine K, material such as sheet fiber or sheet celluloid is inserted fashioning a floor 83 which is disposed normally a slight distance above the bottom of the box and below the plane of the motor base plate 64, as may be observed in Figs. 2 and 5. The false floor 83 is fashioned preferably by inturning the marginal portions thereof to form feet or flanges. Preferably the side margins of the magazine K are lined with strips 84 and 85 of the same material as the false bottom 83, this material be-

ing such as to reduce friction between it and the film F.

Within the box and inwardly of the front wall 54, are brackets 86 which support an elongated strip 87, horizontally disposed, strip 87 having its outer margin upturned forming an upwardly extending flange 88. This strip 87 and its flange 88 extends along the length of the box inwardly of the front wall and constitutes a support for the source of illumination as well as for a glass plate M interposed between the source of illumination and the opening in the front wall. On top of the strip 87 is another elongated strip 89 having a marginal upturned flange 90, which is spaced from the flange 88 to form with such flange a guideway for the lower margin of the film F as it is drawn along the opening in the front wall of the box.

Secured to the strips 87 and 89 are spaced lamp brackets 91 and 92 which receive in endwise electrical association, a single elongated incandescent bulb 93. The bulb 93 is as long as the opening 5 in the front wall of the box so as to afford uniform light projection through such opening. The contacts of the bulb 93 are at its ends and the brackets 91 and 92 provide suitable engagement for the bulb contacts for putting the same in electrical circuit for illuminating purposes.

Further details of the illuminating bulb 93, its construction and arrangement in circuit relation within such a casing are set out more in detail in applicant's co-pending application Serial No. 2,184 filed January 17, 1935.

Supported on top the brackets 91 and 92, in superposed relation, are strips 94 and 95 each having a downturned flanged margin, the downturned flange 96 of the strip 94 aligns with the upturned flange 90 of the piece 89 while the downturned flange 96 aligns with the upturned flange 90 of the piece 89 while the downturned flange 97 of the strip 95 aligns with the upturned flange 88 of the piece 87. The flanges 88, 90, 96, and 97, therefore, constitute guide means for the upper and lower margins of the film F as it is moved along the opening 5 in the front wall of the box. Preferably the extremities of the guide flanges just described are outturned as may be observed in Figure 1 to enable ready entry and exit of the film into and out of the guide means so formed.

Supported on the strip 87, adjacent the left hand end of the box as observed in Fig. 1, is an upstanding spindle 98 on which a roller 99 is rotatably mounted. This roller is counterbored to receive lubricating means 100 and its interior is closed by a ring 101. This roller is provided with top and bottom flanges 102 for guiding the film F as it is bent around the roller and drawn toward the driving roller 71. The roller 99 is so aligned with the guideway formed by the flanges 96, 97, 90 and 88 that no bending of the film occurs between the time it leaves such guideway and contacts the surface of the roller.

At the right hand end of the box as viewed in Fig. 1, a strip 103 is secured across the adjacent end of the box. This strip carries a spindle 104 about which is freely rotatable a roller 105 similar in all respects to roller 99 at the other end of the box. This roller is so disposed with the guide means for the film that the film leaves the roller in straight line direction with respect to the guide means.

Rearwardly of the spindle 104, and on the piece 103 is a second spindle 106 on which a sprocket 107 is freely rotatable. A bearing 108 is interposed

between the sprocket and the plate 103 for purposes well understood.

The roller is provided with teeth 109 for meshing with the holes 75 in the film F. A flat spring 110 is secured at one end 111 to the adjacent end 5 of the box, and its other end bears against the body of the roller 107 to serve as tension means for the film as it is drawn along the opening in the front wall of the box.

Rearwardly of the roller 107 is another spindle 112 bearing a flanged roller 113 about which the film passes as it leaves the magazine K. An idler roller 114 mounted on an adjustable base 115 is adapted to be moved toward and away from the roller 113 for the purpose of insertion and removal of a film.

Secured to the plate 103 to prevent any of the folds or convolutions of the film within the magazine from coming in contact with the rollers 107 and 112, is a guard wall 151. Another guard wall 116 extends toward the rear of the box from adjacent the idler roller 114.

Resting against the rear of the brackets 91 and 92 is an upstanding wall 117 lying behind the incandescent bulb 93 and which may be polished or silvered to serve as a reflector. The upper marginal portion of this wall is bent backwardly at 118 to serve as a reflector for directing light rays against the lowermost margin of the edge glow plate 59 for thus illuminating the plate 30 whenever the bulb is illuminated. To protect the folds or convolutions of film within the magazine K, a sheet of heat insulating material such as asbestos 150 may be secured against the back side of the wall 117. Against this sheet of asbestos is fastened a lining 85 of material such as fiber or celluloid against which the convolutions of the film rub and which facilitates movement of the film through the magazine.

At the entering end of the magazine K, that is 40 the end adjacent the motor H, upstanding horizontally curved guard plates 120 and 121 are suitably secured to the motor base plate 64 to prevent any part of the folded or convoluted film within the magazine from becoming entangled 45 with the motor or the driving roller.

It will be observed that the point of exit of the film F from the magazine K is nearer the front wall of the casing than is the point of entrance. This feature, together with the fact that the 50 direction of entry of the film into the magazine K from the driving roller 71 enables the formation of folds or convolutions within the magazine of rather long lengths, as is clearly shown in Figure 5. The formation of long convolutions enables 55 very ready withdrawal of the film from the magazine for movement along the opening in the front wall of the box.

The fact that the false bottom 83 of the magazine is disposed below the point of entry into the 60 magazine of the film from the driving roller 71 causes the film to take an inclined position as shown in Fig. 2. This prevents too great resistance against the film as it enters the magazine and thus enables the use of a motor of relatively 65 small power for efficiently actuating the apparatus.

The mode of operation of the invention is as follows:

The motor H and the illuminating bulb 93 are 70 preferably connected in electrical circuits so that the same may be energized simultaneously or separately. When it is desired to move the film, the motor switch is closed energizing the motor and also the switch to the bulb 93 is closed for 75

energizing the bulb. Thereupon, the motor draws the film across the opening in the wall of the box and in front of the source of illumination, that is, the bulb 93. Such movement withdraws 5 the film from within the magazine A, at one end, and returns the film to the magazine at the other end. The film is guided in its movement along the glass plate M by means of the guide flanges 88, 89, 97 and 96. Such guiding of the film prevents 10 its being vertically displaced with respect to the glass plate M, thus assuring maximum illuminating effect from the light projected through the drum from the illuminating means 93.

15 The angular adjustment of the idler roller 78 with respect to the driving roller 71 may be made such as to direct the film into the magazine K in any desired direction within the limits of adjustment of the idler roller. It is well understood 20 that said film will leave surface contact between the rollers 71 and 78 in a direction substantially perpendicular to a plane including the axes of the rollers. Thus by swinging the idler roller about the axis of the driving roller 71 this direction 25 may be changed, as is indicated in Fig. 4.

The bottom of the box may be provided with air vents 122, if desired, as may be observed in Fig. 6.

30 Preferably the box is provided with cushioned feet 123 which may be of rubber, rubber composition or any other suitable material.

The boxes as heretofore described are low ones, slightly greater in height than the width of the film plus space for various instrumentalities utilized 35 for moving the film through the box.

It sometimes happens that it is desirable to design a box which is slightly higher than that heretofore described in which event resort may be had to the arrangements shown in Figs. 7 and 40 8 for preventing entanglement of the film in the magazine.

The box L of Figures 7 and 8 is constructed in general as the boxes heretofore described except that it is higher in vertical dimension. In order 45 to prevent the folds or convolutions of film within the magazine K from becoming entangled vertically, a hold down plate 124 may be installed in the box. The plate illustrated in these figures is provided with transverse pieces 125 adapted 50 to have their rear ends passing through suitable slots 126 in the back wall and their front ends adapted to engage against and hook over, as at 127, the inclined portion 118 of the wall 117. In this event the hold down plate 124 is disposed 55 above the film F a distance somewhat comparable to that of the covers of the shallow boxes heretofore described.

The extremities of the flange 88 overlie the lower flanges of the rollers 99 and 105 to prevent 60 dislodgement of such rollers in use.

The front wall 54 is provided with an opening or slot 128 through which a colored transparent strip 129 may be inserted for giving color effect to the matter on the film or band F when the 65 apparatus is in use.

The invention has been described herein more or less precisely as to details, yet it is to be understood that the invention is not to be limited thereby, as changes may be made in the arrangement and proportion of parts, and equivalents may be substituted without departing from the spirit and scope of the invention.

The invention is claimed as follows:

1. In an illuminated sign apparatus of the class 70 described, a casing or box having an elongated

opening along one side wall, an endless band of greater length than said opening in said casing and movable along said opening in edgewise position, said casing providing storage space for the portion of the band not along said opening, means for moving said band continuously along said opening and from and into said storage space, said band adapted to accumulate in folds or convolutions within said storage space, the bottom of said storage space on which the convolutions rest being below the lower edge of the band at its point of departure from said moving means to facilitate formation of folds or convolutions in said space and to reduce friction between band and bottom of storage space. 15

2. In an illuminated sign apparatus of the class described, a casing or box having an elongated opening along one side wall, an endless band possessing sufficient rigidity to stand edgewise in said casing and movable along said opening, said casing providing storage space for the portion of the band not along said opening, said band adapted to accumulate in folds or convolutions within said storage space, the bottom of said storage space being below the lower edge of the band at its point of departure from said moving means to facilitate formation of folds or convolutions in said space, and means for preventing vertical displacement of any of said folds or convolutions. 20

3. In an illuminated sign apparatus of the class described, a casing or box having an elongated opening along one side wall, an endless band of greater length than said opening and possessing sufficient rigidity to stand edgewise in said casing and movable along said opening, said casing providing storage space for the portion of the band not along said opening, said band adapted to accumulate in folds or convolutions within said storage space, and co-operating rollers for moving said band continuously along said opening 25 and from and into said storage space, one of said rollers being movable arcuately with respect to the other roller to vary the line of contact of said rollers for controlling the direction in which the band leaves said rollers and enters said storage space. 35

4. In an illuminated sign apparatus of the class described, a casing or box having an elongated opening along one side wall, an endless band of greater length than said opening and possessing sufficient rigidity to stand edgewise in said casing and movable along said opening, said casing providing storage space for the portion of the band not along said opening, said band adapted to accumulate in folds or convolutions within said storage space, two vertically disposed juxtaposed rollers for engaging opposite faces of said band for moving it, one of said rollers having positive driving engagement with said band, the other of said rollers being arcuately adjustable about said 40 one roller for varying the direction of travel of said band as it leaves said rollers, said other roller also being adapted to be adjusted towards and away from said one roller for insertion and removal of the band. 45

5. In an illuminated sign apparatus of the class described; a casing or box having an elongated opening along one side wall; an endless band of greater length than said opening in said casing and movable along said opening in edgewise position; said casing providing storage space for the portion of the band not along said opening; said band adapted to accumulate in folds or convolutions within said storage space; said storage space having its bottom and certain of its walls 70

75

equipped with smooth lining material immovably arranged within said space to facilitate movement of the band into, in, and through said space; means for moving said band continuously along said opening and from and into said storage space; the bottom of said space being below the lower edge of the band at its point of departure from said moving means to facilitate formation of folds or convolutions in said space; and means 10 for preventing vertical displacement of any of the folds or convolutions in said space.

6. In an illuminated sign apparatus of the class described; a relatively long flexible stiff endless display band possessing sufficient rigidity to stand 15 edgewise, a casing having a display opening for showing but a part of the length of said band; means comprising a magazine for storing in edge-wise standing position that part of the band not along said opening; means for continuously moving said band in edgewise position along said opening and into and out of said magazine; and means for adjusting the direction of entrance of said band into said magazine.

7. In an illuminated sign apparatus of the class 20 described; an elongated flat, low casing having an opening along one side wall thereof; an endless display band of greater length than said casing arranged within said casing and having a part thereof arranged in a series of convolutions with- 25 in a storage chamber of said casing; means for continuously moving said band out of said chamber along said opening and back into said chamber; the point of withdrawal of said band from said chamber being nearer said wall opening than the point of band entrance into said chamber whereby a plurality of band convolutions extending generally in the direction of the length of the chamber are formed in said band within said chamber as said band is moved in use; means 30 for adjusting the direction of band entrance into said chamber for varying the contour of said convolutions; and means for illuminating said band as it is moved along said opening.

8. In an illuminated sign apparatus of the class 35 described; a casing having an opening along one side wall and having a storage magazine; an endless strip or display band of greater length than said casing and of inherently stiff yet pliable material such as celluloid or the like and capable of standing in edgewise position, supported in said edgewise position on the floor of 40 said casing within said magazine; the major por-

tion of said band being in the form of folds or convolutions within the magazine and having a part along said opening; means for continuously moving said band in edgewise position along said opening and through said magazine; and means 5 for controlling the direction of entry of the strip into said magazine which, together with the inherent characteristics of the strip, cause it to form convolutions within said magazine without entanglement and without interference to its free 10 movement into and out of said magazine.

9. In an illuminated sign apparatus of the class described, a casing provided with a display opening, an endless band of the characteristics of celluloid or the like supported in upstanding edge- 15 wise position within said casing, means supporting a portion of said strip in edgewise position along said opening, means supporting other portions of said strip in edgewise position within said casing, means for moving said strip along said 20 opening and thereafter forming portions of said strip into a plurality of edgewise convolutions within said casing, and means adjacent the top and bottom edges of the convoluted portions of said strip for preventing vertical displacement 25 and entanglement of such convolutions.

10. In an illuminated sign apparatus of the class described, a casing having an elongated opening in one side wall, an endless belt of greater length than the opening and adapted to 30 be moved along the opening, a chamber for storing the portion of the belt not being displayed, a plurality of rollers for pulling the belt along said opening continuously and between which rollers the belt passes, and one of said rollers being adjustable with respect to the other to change the line of tangency therebetween for changing the direction of entry of said belt into said chamber.

11. In an illuminated sign apparatus of the class described, a casing having an elongated 40 opening in one side wall, an endless belt of greater length than the opening and adapted to be moved along the opening, a chamber for storing the portion of the belt not being displayed, two cooperating rollers for pulling the belt along said opening 45 continuously and between which rollers the belt passes, said rollers being angularly adjustable with respect to each other to change the line of tangency therebetween for changing the direction of entry of said belt into said chamber. 50

ISIDORE HOLSMAN.
